UNITED STATES PATENT OFFICE.

FRANK L. BURROWS, OF CRANSTON, RHODE ISLAND, ASSIGNOR TO CHARLES A. WILKINSON, OF WARWICK, AND DUTEE WILCOX, OF PROVIDENCE, RHODE ISLAND.

HOLDER FOR ADJUSTABLE GUARDS FOR EYEGLASSES.

SPECIFICATION forming part of Letters Patent No. 585,813, dated July 6, 1897.

Application filed April 5, 1897. Serial No. 630,724. (No model.)

To all whom it may concern:

Be it known that I, FRANK L. BURROWS, of the town of Cranston, in the county of Providence, in the State of Rhode Island, have invented a certain new and useful Improvement 5 in Holders for Adjustable Guards for Eyeglasses; and I declare the following to be a specification thereof, reference being had to the accompanying drawings.

- 10 Figure 1 is an elevation of a pair of eyeglasses having my improved holder for the adjustable guards thereof. Fig. 2 is a perspective view of the adjustable guard with the cork and shell combined therewith. Fig.
- 15 3 is a perspective view of one of the eyeglasses with the post and double-pronged holder thereon. Fig. 4 shows said holder in side elevation. Fig. 5 is a cross-section on line xx of Fig. 3. Fig. 6 is a plan of the guard 20 before bending it into shape. Fig. 7 illustrates the manner in which the adjustable guard is engaged with the holder.

Like letters indicate like parts.

My invention relates to that class of eyeglasses made with adjustable guards; and it 25 consists in forming said guard near its lower end with certain slots and in providing a double-pronged holder of peculiar shape upon the eye-rim, which is engageable with said 30 guard through the slots thereof, as hereinafter particularly described.

In the drawings, A represents the lenses, B the rims for the same, and C the spring. The 35 spring C is fastened in position by screws aa , which confine it within the grooves on the outer end of the posts D, the latter being soldered upon the eye-rims B, as shown. The usual connecting-straps are shown at ss .

The guard is made with the cork pieces E, 40 which are held by the turned edges of the metallic shell F in the usual manner. A metallic strip G, Fig. 6, has near one end the rectangular oblong slot b and near its opposite end the round hole c and slot d , the latter of which is shaped like a keyhole, having 45 its outer end of a larger diameter than its inner end.

On the eye-rim B is a double-pronged holder H, made of cylindrical wire and consisting 50 of a bent portion which is soldered to the

eye-rim, one of the prongs, m , extending radially from the curved eye-rim B and the other of the prongs, n , extending substantially in a direction parallel with the eye-rim. The prong or hook n has its head flattened out, so that it 55 is thinner than the body of the holder, but somewhat wider, all as shown in Figs. 3 and 4.

The strip G having been inserted longitudinally between the cork E and the shell F, as illustrated in Fig. 5, has the end which is 60 made with the slot b bent at a right angle and the opposite end bent into a curved or **U** shape.

The guard and holder are engaged with each other, as shown in Fig. 7. The broadened end of the prong or hook n is inserted in the slot d of the guard G, while the latter is held, as shown in said figure, in a direction at a right angle with the plane of the lens or the eye-rim. The guard after it is so engaged 70 is swung around until it extends in the same plane with the lens or eyerim and then is swung up in the same plane until the prong m of the holder H enters the hole c of the guard G. The other end of the guard G is 75 then bent or sprung so that its slot b engages with the bent ends of the connecting-strap s , as in Fig. 1. By this construction I dispense with the screw-fastening heretofore commonly used to secure the lower end of the 80 guard to a post extending from the eye-rim. The end of the prong n furnishes an edge against which the spring-guard bears. The turning of the holder H a quarter-turn in the slot d of the guard locks the parts together, 85 while the subsequent engagement of the prong m in the hole c confines the parts in their proper position and prevents lateral displacement or twisting.

I claim as a novel and useful invention and 90 desire to secure by Letters Patent—

1. The improved holding device for adjustable guards for eyeglasses herein described, consisting of the combination with an eye-rim, of a double-pronged holder, one end extending radially from said rim and the other parallel thereto, and a guard, having a slot 95 near one end and two slots near its opposite end, with which last-named slots, respectively, the prongs of said holder are engageable, a 100

post upon the eye-rim, and a spring and connecting-strap fastened upon said post, the end of said connecting-strap being engageable with the first-mentioned slot of the guard, 5 substantially as specified.

2. In an eyeglass having a pair of eye-rims, a post on each eye-rim, a spring and connecting-straps on said posts with the ends of said connecting-straps bent inwardly, the combination of a bent holder on each eye-rim and made of cylindrical wire, one end or prong thereof extending radially from the eye-rim and the other end or prong thinned and broadened at its extremity and extending parallel 10 with said eye-rim, and two guards, each provided at one end with a slot to receive a bent

end of a connecting-strap and provided at the opposite end with two openings, one of which is a round aperture sufficient to receive the first-mentioned prong of the adjacent holder and the other end of which is a round aperture of like diameter with a slot extending longitudinally therefrom sufficient to receive the broadened thinned edge of the other prong of said holder, all arranged and operating substantially as shown and for the purpose specified. 20 25

FRANK L. BURROWS.
